UNITED STATES PATENT OFFICE.

GEORGE W. KONE, OF KANSAS CITY, MISSOURI.

KEYLESS PADLOCK.

No. 901,972.

Specification of Letters Patent.

Patented Oct. 27, 1908.

Application filed January 16, 1905. Serial No. 241,312.

To all whom it may concern:

Be it known that I, GEORGE W. KONE, a citizen of the United States, residing at Kansas City, in the county of Jackson and State of Missouri, have invented certain new and useful Improvements in Keyless Padlocks, of which the following is a specification.

My invention relates to improvements in locks.

10 It relates particularly to permutation padlocks in which the use of keys is dispensed with.

The object of my invention is to provide a keyless padlock of the character described 15 which is capable of being set to many combinations, which is reliable in operation, not easily disordered, is cheap to manufacture, and which possesses great durability.

My invention provides a construction in 20 which the operator may quickly change the combination.

It provides further a construction of lock by which the operator may easily adjust the tumblers to the proper position for unlocking 25 by the aid of the sense of feeling alone, thus enabling one to unlock the mechanism in the dark.

Other novel features are hereinafter fully described and claimed.

30 In the accompanying drawings illustrative of my invention, Figure 1 is a central longitudinal sectional view of the padlock in the closed or locked position. Fig. 2 is a forward end elevation of the padlock. Fig. 3 is an end view of the shackle engaging bolt. Fig. 4 is an end elevation of the padlock with the cap and shackle removed. Fig. 5 is a side elevation of the padlock. Fig. 6 is a rear end view of a tumbler. Fig. 7 is an 40 end view of the inner member of a tumbler.

Similar characters of reference denote similar parts.

1 denotes the crown having a central tubular part 2 closed at its rear end and having a 45 lateral opening 3 to receive the shackle 4, the inner or free end of which is notched to receive a slide bolt 5 reciprocatively mounted in the tubular portion 2 of the crown 1. The slide bolt 5 preferably comprises a cup 50 shaped body the bottom of which is provided with a recess 6 adapted to receive therein the notched end of the shackle. A coiled spring 7 bears at one end against the slide bolt 5 and at the other end upon the inner side of the closed end of the crown 1.

The tension of the spring 7 is such as to normally force the slide bolt 5 forward into engagement with the shackle.

Secured at one end forward of the opening 3 to the crown 1 is a connecting member 8 comprising preferably a tubular post longitudinally slotted at one side and having its other end externally screw threaded. Rotatively mounted on the screw threaded end of the post 8 is a cap 9 to which the shackle 4 is pivoted. Reciprocatively mounted in the post or tube 8 and extending through the central portion of the cap 9 is a member comprising preferably a slidable bar having a series of lateral projections 11 extending laterally through the slot 10 of the post 8, the slideable bar being denoted by 12. The rear end of the bar 12 is provided with a projection 13 which enters a hole 14 in the bolt 5 and prevents rotation of the bolt 5 in the crown. 75 In the outer end of the post disposed diametrically opposite the slot 10 is a slot 15 in which is mounted a projection 16 on the bar 12 which with the projections 11 prevent rotation of the bar in the post. 80

The outer of the projections 11 is adapted when the bar 12 is not moved to enter a recess or hole 17 provided in the cap 9 and prevents rotation of the cap on the post 8, but when the bar 12 is moved inward the projection is withdrawn from the recess 17 and the cap may be unscrewed and detached from the post to enable the operator to remove and change the combination of the tumblers. 90

The tumblers are rotatively mounted between the cap 9 and crown 1 and encircle the post 8 and bar 12. Each tumbler comprises an outer annular member 18 preferably of cup like form and provided on its inner periphery with a plurality of circularly arranged recesses 19 adapted to receive a rearwardly extending projection 20 provided on the rear side of the inner member 21, which is also preferably of annular cup like form, the transverse or bottom portion of which is disposed so as to engage with and prevent movement of the bar 12 when the inner member is disposed in any other than a certain position. The bottom of each inner member of each tumbler is provided with a slot 22 through which the outer adjacent projection 11 may pass when all the tumblers are disposed so that the slots 22 are in alignment with the projections 11. When so posi- 110

tioned the bar 12 may be moved, thus forcing back the slide bolt 5 against the pressure of the spring 7 and releasing the shackle 4 from the bolt 5 and permitting the withdrawal of 5 the shackle from the opening 3. When the bar 12 is moved inward the outer projection 11 is withdrawn from the hole or recess 17 and the cap can be removed as above described. The tumblers may then be removed from the 10 post 8 and the inner member 21 of each turned to any desired position.

The outer member 18 of each tumbler is provided with a series of transverse grooves 23 disposed parallel with the axis of the 15 member and arranged at equal intervals around its outer periphery thus dividing the periphery into a series of raised portions corresponding in number to the number of recesses 19. One of said raised portions may 20 be provided with a projection 24 which furnishes a starting point by which the operator may by feeling properly rotate the tumbler to the position required for unlocking the padlock. For convenience another projection 25 differing in configuration from the projection 24 may be provided on the raised portion disposed diametrically opposite the one having thereon the projection 24. The projection 24 may be pointed and the projection 25 flattened for effecting a ready recognition between them. The other raised portions on the outer member 18 may be numbered or provided with other suitable distinguishing devices. The periphery of the 35 crown 1 may be provided with one or more grooves 26 to serve as guides for properly locating the different tumblers. When disposed in the locked position as shown in Fig. 1, the projections 11 lie respectively forward 40 of the bottom of the inner members 21, thus permitting free rotation of the tumblers to and fro.

The outer members are rotatively fitted respectively in each other and in the crown, 45 a shoulder being provided on the rear end of each outer member for this purpose. The cap 9 is mounted in the outer or forward one of the outer members and prevents forward movement of the inner member of the outer 50 tumbler, the outer members of the rear tumblers preventing forward movement of the other inner members 21.

To unlock the padlock, the combination being known to the operator, he turns the 55 tumblers to positions in which the slotted positions of the inner members 21 will be in alinement with the projections of the bar 12. The bar 12 is then moved rearwardly, thus moving the bolt 5 and releasing therefrom 60 the shackle 4. To lock the device, it is but necessary to insert the free end of the shackle into the opening 3. The shackle will force the bolt 5 rearwardly until the projection at the rear edge of the notched end of the

shackle is opposite the hole or recess 6, at 65 which time the spring 7 will force the bolt 5 forward and causing the bolt to enter the notch in the shackle.

Having thus described my invention, what I claim and desire to secure by Letters Pat- 70 ent, is:—

1. The combination with the shackle, of the crown provided with an opening to receive the shackle, a cap, a member connecting the crown and cap and from which the cap is detachable, a slide bolt mounted in the crown and adapted to engage the shackle, a slidable member mounted in the connecting member and adapted when moved in one direction to free the slide bolt from the shackle and provided with means for releasably engaging and preventing detachment of the cap, a plurality of tumblers rotatively mounted between the crown and cap, each tumbler when disposed in a certain position permitting reciprocation of the slidable member and provided with means for engaging and holding said slidable member when the tumbler is turned to any other position, and a spring for forcing the slide bolt and the slidable member into the locked positions. 85

2. The combination with the shackle, of the crown provided with an opening to receive the shackle, a tube secured at one end to the crown, a cap detachably secured to the other end of the tube, a slide bolt adapted to engage the shackle, a slide bar reciprocatively mounted in the tube and adapted when moved in the proper direction to move the slide bolt so as to free it from the shackle 100 and provided with means for releasably engaging and preventing detachment of the cap, a plurality of tumblers rotatively mounted between the cap and crown and encircling the tube and slidable member and provided each with means for engaging and holding the slidable member, but permitting movement thereof when the tumbler is disposed in a certain position, and a spring for forcing the slide bolt and the slidable member into the locked positions. 105

3. The combination with the shackle, of the crown provided with an opening to receive the shackle, a cap, a member connecting the crown and cap from which the cap is detachable, a slide bolt for engaging and holding the shackle in the crown, a slidable member mounted in the connecting member for moving the slide bolt to disengage it from the shackle and provided with means for engaging the cap and preventing detachment of the cap from the connecting member, a plurality of tumblers rotatively mounted between the cap and crown and encircling the connecting member and provided each with means for preventing the movement of the slidable member when the said tumbler is disposed in any other than a certain posi- 115 120 125

tion, and a spring for forcing the slide bolt and the slidable member into the locked positions.

4. The combination with the shackle, of 5 the crown provided with an opening to receive the shackle, a cap, a tube secured at one end to the crown and having the cap detachably secured to its other end, a slide bolt for holding the shackle when the shackle 10 is inserted in said opening in the crown, a slide bar reciprocatively mounted in the tube and adapted to engage the slide bolt and free it from the shackle when the bar is properly moved, and provided with means 15 for engaging and preventing detachment of the cap excepting when the slide bar is moved inward, a plurality of tumblers rotatively mounted between the cap and crown, and provided each with means for engaging 20 and preventing depression of the slide bar excepting when the tumbler is disposed in a certain position relative to the slide bar, and a spring for forcing the slide bolt and slide bar into the locked positions.

25 5. The combination with the shackle, of the crown, a cap, a member secured at one end to the crown and detachably secured at the other end to the cap, the crown having an opening to receive the shackle, a slid- 30 able member reciprocatively mounted in the connecting member and provided with means for releasably engaging and preventing detachment of the cap, a slide bolt for engaging the shackle when the shackle is inserted in 35 said opening in the crown, and movable by the slidable member out of engagement with the shackle, means for moving the slide bolt into engagement with the shackle, said means being employed to force the slid- 40 able member to engage the cap, and a plurality of tumblers rotatively mounted between the cap and crown and provided each with means for engaging and preventing sliding movement of the slidable member when the 45 tumbler is disposed in any other than a cer- tain position.

6. The combination with the shackle, of the crown having an opening to receive the shackle, a slide bolt movable in the crown to 50 engage and hold the shackle, a spring for so moving the slide bolt, a cap, a member connected to the crown at one end and detachably secured to the cap at the other end, a slidable member mounted in the connecting 55 member and at one end extending through the cap and at the other end engaging the slide bolt, said spring serving to engage the slidable member with the cap, and a plurality of tumblers rotatively mounted be- 60 tween the cap and crown and provided each with means for engaging and preventing sliding of the slidable member when the tumbler is disposed in any other than a cer- tain position.

7. The combination with the shackle, of 65 the crown having an opening to receive the shackle, a slide bolt in the crown for engag- 70 ing the shackle, a spring for moving the slide bolt so as to engage the shackle, a tube se- cured at one end to the crown, a cap de- tachably secured to the other end of the tube, a slide bar reciprocatively mounted in the tube for moving the slide bolt against the pressure of the spring and provided with 75 means when in a certain position for engag- 80 ing and locking the cap from disengagement with the tube, said spring forcing the slide bar to engage the cap, and a plurality of tumblers rotatively mounted between the cap and crown and provided each with means for engaging and preventing sliding of the slidable member when the tumbler is in any other than a certain position.

8. The combination with the shackle, of 85 the crown having an opening to receive the shackle, a slide bolt in the crown for engag- 90 ing the shackle, a spring for holding the slide bolt in such engagement, a cap, a connecting member secured to the crown and detach- ably secured to the cap, a slidable member 95 mounted in said connecting member and reciprocative through a hole in the cap and adapted when moved in the proper direction to disengage the slide bolt from the shackle and provided also with means for releasably 100 engaging the cap and preventing its detach- ment from the member to which it is secured, said spring forcing the slidable member into engagement with the cap, and a plurality of tumblers rotatively mounted between the 105 cap and crown and provided each with means for engaging and preventing move- 110 ment of the slidable member when the tumbler is disposed in any other than a cer- tain position.

9. The combination with a shackle, of the crown having an opening to receive the shackle, a slide bolt in the crown for engag- 115 ing the shackle, a spring for moving the slide bolt into engagement with the shackle, a cap, 120 a tube secured at one end to the crown and secured detachably at the other end to the cap, a slide bar reciprocatively mounted in the tube and extending through the cap and adapted to engage and force the slide bolt out of engagement with the shackle, and pro- 125 vided also with means for releasably engag- ing and preventing detachment of the cap from the tube, said spring forcing the slide bar into engagement with the cap, and a plu- 130 rality of tumblers rotatively mounted be- 135 tween the crown and cap and provided each with means for engaging and preventing movement of the slide bar when the tumbler is disposed in any other than a certain posi- 140 tion.

10. The combination with the shackle, of the crown, means provided in the crown for

- engaging and holding the shackle, a tube secured at one end to the crown and having a longitudinal slot, a cap detachably secured to the other end of the tube, a bar slidably mounted in the tube and provided with a plurality of projections extending through the slot in the tube and provided also with means for releasably engaging with and preventing detachment of the cap from the tube, a plurality of tumblers rotatively mounted between the cap and crown and provided with means for engaging respectively the projections on the slide bar and preventing the movement of the bar when the tumblers are disposed in any other than a certain position relative to the slide bar, and a spring for forcing the shackle engaging means and the slide bar into the locked positions.
11. The combination with the shackle, of the crown having an opening to receive the shackle, a cup shaped slide bolt mounted in the crown and provided in its bottom with a hole to receive the shackle when the same is inserted in said opening, a spring for moving the slide bolt to engage the shackle, a cap, a tube secured at one end to the crown and detachably secured at the other end to the cap, a slide member mounted in the tube and adapted when moved in the proper direction to disengage the slide bolt from the shackle and provided with releasable means for engaging and preventing detachment of the cap, said spring forcing the slide member into engagement with the cap, and a plurality of tumblers rotatively mounted between the cap and crown and provided each with means for engaging and holding the slide member from movement when the tumbler is in any other than a certain position.
12. The combination with the shackle, of the crown having an opening to receive the shackle, a tubular slide bolt movable in the crown to engage and hold the shackle, a spring for so moving the slide bolt, a tube secured at one end to the crown, a cap detachably secured to the other end of the tube, a slide bar mounted in the tube and extending through the cap and adapted when moved in the proper direction to disengage the slide bolt from the shackle, and provided also with means for engaging and preventing detachment of the cap from the tube, said spring forcing the slide bar into engagement with the cap, and a plurality of tumblers rotatively mounted between the cap and crown
- and provided each with means for engaging and preventing movement of the slide bar when the tumbler is in any other than a certain position.
13. The combination with the shackle, of the crown having an opening to receive the shackle, means provided in the crown for releasably engaging the shackle, a member connecting the crown with a cap, the cap detachably secured to said connecting member, a slide member extending through the cap and adapted when moved in the proper direction to release the shackle from the shackle engaging means, the slide member having a plurality of projections and being provided also with releasable means for engaging and preventing detachment of the cap from the connecting member, a plurality of tumblers rotatively mounted between the cap and crown and provided with means for engaging respectively the said projections for preventing movement of the slide member when the tumblers are in any other than a certain position, and a spring for forcing the shackle engaging means and the slide member into the locked positions.
14. The combination with the shackle, of the crown, means provided in the crown for releasably engaging the shackle, a tube having a longitudinal slot and secured at one end to the crown, a cap detachably secured to the other end of the tube, a slide member mounted in the tube and having a plurality of projections extending through the slot, the slide member extending through the cap, said slide member having releasable means for engaging and preventing detachment of the cap from the tube, a plurality of tumblers rotatively mounted between the cap and crown and comprising each an inner and an outer member circumferentially adjustable relative to each other, the inner members being adapted to engage said projections respectively and prevent movement of the slide member when the outer members have been disposed in any other than a certain position, and a spring for forcing the slide member and shackle engaging means into the locked positions.
